US0D1036539S

(12) **United States Design Patent** (10) Patent No.: **US D1,036,539 S**
Kondamuri et al. (45) Date of Patent: ** Jul. 23, 2024

(54) **GLASSES FRAMES**

- (71) Applicant: **PAIR EYEWEAR, INC.**, New York, NY (US)
(72) Inventors: **Nathan Kondamuri**, Brooklyn, NY (US); **Sophia Edelstein**, Brooklyn, NY (US); **Lee Zaro**, Rancho Palos Verdes, CA (US)
(73) Assignee: **PAIR EYEWEAR, INC.**, New York, NY (US)
(**) Term: **15 Years**
(21) Appl. No.: **29/914,180**
(22) Filed: **Oct. 13, 2023**

Related U.S. Application Data

- (62) Division of application No. 29/775,184, filed on Mar. 22, 2021, now Pat. No. Des. 1,016,126.
(51) **LOC (14) Cl.** **16-06**
(52) **U.S. Cl.** **USPC** **D16/300**
